Filed Apr. 26, 1971, Ser. No. 137,751

Term of patent 14 years

Int. Cl. D21—02

U.S. Cl. D34—5

FIG. 1 is a perspective view of a golf putting device showing my new design;

FIG. 2 is a rear view of the design of FIG. 1.

The opposite unseen portion of FIG. 1 is the same as that shown on the near side.

My design is characterized by a partially hollowed housing having the shape of a golf putter from which leads the putting runway, all as shown.

I claim:

The ornamental design for golf putting device, as shown and described.
